CLAIM

The ornamental design for a corner awning extension for office pod, as shown and described.

DESCRIPTION

FIG. 1 is a perspective view of a corner awning extension for office pod according to the design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The dash-dot-dash broken lines show environmental structure and form no part of the claimed design.

The even broken lines show portions of the article that form no part of the claimed design.

The dash-dot-dot-dash broken lines depict the bounds of the claimed design and form no part of the claimed design.

1 Claim, 7 Drawing Sheets
